CARRIAGE RETURNING MECHANISM FOR
TYPEWRITERS OR LIKE MACHINESHenry J. Hart, West Hartford, Conn., assignor to
Royal Typewriter Company, Inc., New York,
N. Y., a corporation of New York

Application October 12, 1950, Serial No. 189,791

20 Claims. (Cl. 197—65)

1

This invention relates to carriage returning mechanisms for typewriters or like machines, and more particularly to an improved mechanism providing a mechanical advantage for multiplying the effort initially applied to a carriage returning member, so that the starting friction and inertia of the carriage may be overcome more easily when the carriage is moved from a position of rest towards its starting position for the commencement of a new line of typing.

Although the invention is applicable generally to typewriters or like machines of different constructions, operated manually or by power, it is especially advantageous when used in connection with manually operated machines, since, by virtue of the invention the fatigue ordinarily resulting from repeatedly returning a carriage by hand is reduced.

In most conventional manually operated typewriters, a single lever mounted on the carriage serves both for operating line spacing mechanism to rotate the sheet feeding platen, and for returning the carriage to its line starting position. The present invention may be embodied in constructions of this kind in such manner that when the combined line spacing and carriage return lever is moved initially, a novel normally ineffective mechanical advantage driving mechanism will be rendered effective and continued movement of the lever will then effect the line spacing operation while the driving mechanism starts the carriage return movement at reduced speed, and with the application of reduced effort on the lever.

An object of the invention is to provide a carriage returning mechanism, operative during the initial movement of a carriage returning member, for multiplying the effort applied to the member, and transmitting the multiplied effort to the carriage so as to reduce the amount of effort required to be applied to the member for overcoming the starting friction and inertia of the carriage.

Another object of the invention is to provide a mechanism of the character referred to which includes or is operated by a combined line spacing and carriage returning lever.

A further object of the invention is to provide a mechanism of the kind referred to which is adapted to be operative for moving the carriage only when the carriage is within a predetermined range of its positions relative to the main or stationary frame of the machine, the arrangement being such that the line spacing mechanism may be operated independently of

2

the carriage returning mechanism when the carriage is within a different range of positions.

Other objects of the invention will become apparent from a reading of the following description, the appended claims, and the accompanying drawings, in which:

Figure 1 is a view, partly in rear elevation and partly in vertical section, showing parts of a typewriter frame and carriage at the right hand end of the machine;

Figure 2 is a view, partly in rear elevation and partly in vertical section, of parts of the frame and carriage at the left hand end of the machine, Figures 1 and 2 together constituting a composite view separated on the line x—x of each;

Figure 3 is a fragmentary, horizontal sectional view on the line 3—3 of Figure 1, some parts being shown in elevation;

Figure 4 is a vertical sectional view on the irregular line 4—4 of Figure 3, drawn on an enlarged scale;

Figure 5 is a fragmentary detail view, partly in rear elevation and partly in section, showing a gripper pawl and associated parts;

Figure 6 is a fragmentary vertical sectional view on the line 6—6 of Figure 5;

Figure 7 is a fragmentary view, partly in rear elevation and partly in vertical section, showing certain of the parts illustrated in Figure 1, but in positions different from those shown in Figure 1; and

Figure 8 is a detail view, partly in elevation and partly in section, showing a part of a resilient link construction.

In considering the drawings, it will be helpful to bear in mind that Figures 1, 2, 5 and 7 show the construction as viewed from the rear of the machine, so that parts shown at the right of these views are at the left of the machine as viewed from the front.

The invention is illustrated as being embodied in a typewriter of generally conventional construction including a stationary main frame, a part of which is indicated at A as being equipped with a fixed bottom rail 1 on which a carriage B is mounted for letter spacing and return movements by means of a top rail 2 fixed to the carriage and adapted to roll upon ball 3, which in turn roll upon the bottom rail 1. In order to keep the balls properly spaced from each other, each is equipped with a toothed ring 4 which meshes with rack teeth 5—5' on the rails 1 and 2, respectively. The bottom rail 1 is formed with an overhanging, rearwardly projecting ledge or bar 6. Retainers 7 having bottom parts 8 ex-

tending under the ledge 6 are secured adjustably to the carriage rail 2 by screws 9 passing through inclined slots 10 and having threaded connection with the rail 2. The retainers 7 hold the carriage against upward movement with respect to the frame rail 1, and thus cooperate with the balls 3 and rails 1 and 2 to constrain the carriage against movements transverse to the letter spacing and return travel of the carriage.

The carriage structure includes end plates 11 and 12 secured to the rail 2 by screws 13. Conventional means such as a spring drum, a part of which is shown at 14 in Figure 1, and a draw band 15 wound around the drum and connected to the carriage, urges the latter to move in the letter spacing direction under the control of an escapement mechanism, not shown. A platen C is journaled on the end plates 11 and 12 for rotary line spacing movements in the usual manner.

A margin stop rack bar 16 is secured to the end plates as shown in Figure 7, the ends of the bar 16 being threaded as at 17 to receive nuts 18 screwed against opposite faces of the associated end plates. The bar 16 carries the usual margin stops, one of which is shown at 19 in Figure 7, the stop 19 shown being the "left" margin stop, the position of which on the bar 16 determines the extent of the return travel of the carriage, and hence the width of the right hand margin on the work sheet. For this purpose the stop 19 is cooperable with a center stop assembly generally designated 20, and comprising a tabular and margin stop lever 21, a line lock blade 22, and a cushion lever 23, both the blade 22 and the lever 23 being pivoted on the lever 21 as at 24. The line lock blade 22 may be connected to line lock mechanism of any suitable kind, not shown. The cushion lever 23 is urged by a spring 25 to a position displaced slightly to the right of the position shown in Figure 7, so that when it is engaged by the margin stop 19 the carriage will be brought to rest at the end of its return movement with a reduced or minimized shock effect.

The machine illustrated is equipped with line spacing mechanism generally similar to the mechanism shown in the patent to Hess 1,208,154. As shown in Figures 1 and 4, the end plate 12 is formed with a horizontal ledge 26 terminating in a down-turned skirt 27 which, together with the end plate proper, provides for the journaling of the platen shaft 28. A line spacing lever member 29, which also serves as a carriage returning handle or lever, is secured to a pintle 30 which is rockable in a bearing 31 having threaded connection at 32 with the end plate ledge 26. The pintle 30 is held against axial shifting in the bearing 32 by a screw 33 threaded into the lower end of the pintle to press against a gear segment 34 on the lower end of the pintle and serving as a pintle retaining washer as well as performing a gear function to be described later. Rocking of the line spacing lever 29 in the direction for effecting line spacing and carriage returning movement is limited by its engagement with an adjustable eccentric head screw 35, and rocking of the lever 29 in the opposite direction to its normal position is limited by its engagement with a stop lug 36 forming part of an adjustably mounted stop plate 37. The lever 29 is urged toward its normal or inoperative position, determined by the stop lug 36, by a spring 38 interposed between a hook 39 on the gear sector 34 secured to the pintle 30, and an ear 40 on the plate 37, most clearly shown in Figure 3.

Pivoted at 41 on the short arm 42 of the line space lever 29 is one end of a link 43, the other end of which is connected, at a point not shown, to an arm 44 mounted to rock about the platen axis. A line spacing pawl 45 is pivoted as at 46 on the arm 44, and is adapted to engage a ratchet wheel 47 fixed to the platen for rotating the latter in step movements in response to rocking of the combined line spacing and carriage returning lever 29. Normally, the nose of the pawl 45 rests upon a shield 48 which holds the nose out of engagement with the ratchet wheel 47 until after the line spacing lever 29 has been turned a predetermined amount about the axis of the pintle 30. The shield 48 is provided with a handle or finger piece 49 by means of which the shield may be turned about the axis of the platen for varying the portion of the shield over which the pawl 45 must ride before it drops into engagement with the ratchet wheel 47, the adjustment of the shield 48 thus providing for the selection of single, double, or triple line spacing movements of the platen in response to a single stroke of the lever 29.

With the exception of the provision of a gear segment 34 instead of a washer formed with a hook such as the hook 39, the construction described so far is similar to the construction customarily embodied in the Royal standard typewriter, and therefore does not per se constitute the present invention. The invention resides in other parts to be described, and in the combination of such other parts with each other and with the conventional parts referred to above.

In accordance with the invention, novel mechanism is provided for reducing the amount of effort required to be applied to a member, such as the line spacing and carriage returning lever 29, for overcoming the starting friction and inertia of the carriage, and initiating its return movement toward the right. Preferably, the arrangement is such that a mechanical advantage is provided for reducing the force required to be applied to the lever 29 until after the return movement of the carriage has been started at reduced speed, and, after the carriage has been started, a relatively direct connection between the lever 29 and the carriage is rendered effective for returning the carriage at full speed, that is, at the same speed as that at which the lever 29 is continued in movement. In the form shown, the reduced speed and minimized effort phase of the carriage return movement takes place while the lever 29 is being rocked from its normal position to the position in which its short arm 42 engages the stop 35, the stop 35 then bringing about a direct connection between the lever 29 and the carriage, so that continued movement of the lever will move the carriage toward the right at the same speed as that at which the lever is moved.

In the preferred construction shown, the frame rail ledge or bar 6 is formed with a series of serrations or tooth parts 59 which extend from the left hand end of the bar (right hand end as viewed in Figures 1, 5 and 7) toward the opposite or right hand end of the bar 6, but terminate short of the opposite end. A gripper part or device, as shown a pawl 51, adapted to cooperate with the serrated portion 59 of the bar 6, is carried by a plate 52 formed with slots 53 traversed by headed screws 54 secured to the carriage rail 2, and mounting the plate 52 for limited sliding movement on the carriage. A pawl retainer 55 75 is secured to the plate 52 by screws 56, and is

formed with an offset part 57 and a tab 58 which projects behind the pawl 51, so that the latter is retained between the plate 52 and the tab 58. The pawl 51 is formed with a V-shaped notch 59 which normally receives a headed screw 60 on the plate 52, so as to maintain the pawl in its normal position in which a tooth 61 on the pawl is disposed above and out of engagement with the serrations 50 on the bar 6. The pawl 51 is also formed with a gripper lug 62 which extends under the smooth bottom surface of the rail 6, and normally has relatively free sliding engagement with this surface so as not to interfere with the traveling of the carriage in both the letter spacing and the carriage returning directions.

Mechanism operable by initial rocking of the line spacing lever 29 is provided for moving the pawl 51 from its normal position shown in Figure 1 to its operative position shown in Figure 7, in which it grips the frame mounted rail 6 by engagement of the tooth 61 with the serrations 50, and engagement of the gripper lug 62 with the bottom of the rail 6. The mechanism is such that continued rocking of the line spacing lever 29, following movement of the pawl 51 to its gripping position, starts the carriage on its return movement at reduced speed and with reduced effort being required to be applied to the line spacing lever. In the form shown, a link generally designated 63 is connected as at 64 to the pawl 51, and is connected as at 65 to a two-armed lever member 66 which is pivoted at 67 on a bracket 68 secured to the end plate 12. Preferably, the link 63 is constructed to be yieldable longitudinally, and to this end it is constituted by a coiled spring 63^a and end connectors formed as screw eyes 63^b, as shown in Figure 8.

The top part of the lever member 66 is formed as a toothed gear segment 69 adapted to receive effort applied for effecting the initial carriage returning movement. The segment 69 meshes with a toothed segment 70 formed on a down-turned part of one arm of a lever 71 mounted to turn about a pivot bearing 72 clamped to the end plate ledge 26 by the eccentric head stop post 35 previously referred to. The other arm of the lever 71 is formed with a toothed segment 73 which meshes with the segment 34 secured to the line spacing lever pintle 30. When the line spacing and carriage returning lever 29 is rocked for effecting line spacing movement of the platen and return movement of the carriage, the gear segment 34 and the lever 71 turn so as to rock the lever 66 counterclockwise, as viewed in Figure 1, thereby pulling the link 63 toward the right, as viewed in Figure 1, so as to move the pawl 51 into gripping engagement with the rail 6. Continued rocking of the lever 66 will then operate with the mechanical advantage it provides for starting the return movement of the carriage.

Operation

Normally, when the carriage has reached the position it occupies after typing a line, the parts will be in the positions shown in Figures 1 and 3 with the line spacing lever 29 held against the stop lug 36 by the spring 38. The lever 66 will be in the position shown in Figure 1, so that the contracted link 63 will hold the pawl 51 with its notch 59 receiving the screw 60 on the slide 52, the pawl 51 thus being held in its normal, ineffective position, disengaged from the serrated portion of the bar 6. The line spacing pawl 45 will rest upon the shield 48, which may be as-

sumed to be in the adjusted position for determining single line spacing incremental movements in response to rocking of the line spacing and carriage returning lever 29.

When the line spacing lever 29 is rocked initially from its normal position, indicated by the line *a* in Figure 3, to the partially rocked position indicated by the line *b*, the lever 66 will be rocked counterclockwise so as to move the link 63 toward the left (toward the right as viewed in Figures 1 and 7), and thereby move the pawl 51 to the effective connecting position shown in Figure 7, in which the pawl tooth 61 engages the serrated part 50 of the bar 6, and the pawl gripper lug 62 grips the bottom of the rail 6. When the pawl 51 has been so positioned, the connection 65 between the link 63 and the lower end of the lever 66 is anchored to the frame A by the pawl and the link 63 and cannot move with respect to the frame A, except slightly as permitted by yielding of the link spring 63^a, so that the connection 65 provides, in effect, a substantially fixed fulcrum for the lever 66. Consequently, further rocking movement of the lever 66 from the position indicated by the line *b* in Figure 3 to the position indicated by the line *c*, by effort applied to the top part 69 of the lever 66, will exert multiplied force on the pivot 67 and end plate bracket 68 substantially parallel to the directions of carriage letter spacing and return travel, and will thus drive the carriage toward the right (toward the left as viewed in Figures 1 and 7). The mechanical advantage thus provided is due to the fact that the lever arm between the top part 69 of the lever 66 and the fulcrum 65 is considerably longer than the lever arm between the pivot 67 and the fulcrum 65.

During the movement of the line spacing lever from the position indicated by the line *c* to the position indicated by the line *d*, the reduced speed carriage return movement will be continued, and the line spacing pawl 45 will move off the shield 48 so as to engage the ratchet wheel 47 and rotate the platen C a single line spacing increment. When the line spacing lever has reached the position indicated by the line *d*, its short arm 42 will engage the stop post 35 so as to terminate rocking of the lever about its pivot 30, stop the line spacing movement of the platen, and provide a direct driving connection between the lever 29 and the carriage for returning the carriage at full speed, that is, at the same speed as that at which the line spacing lever is continued in translatory movement towards the operator's right, without rocking. The direct driving of the carriage towards the right, while the slide 52 and pawl 51 are stationary relative to the bar 6, will relax the slightly stretched spring 63^a, enabling it to expand so as to push the pawl notch 59 against the pin 60 on the slide 52, and thus cause the pawl tooth 61 to be disengaged from the serrated portion 50 of the bar 6. During continued return movement of the carriage, the pawl 51 will slide idly on the bar 6. When the carriage reaches the end of its return movement, and the lever 29 is returned to its normal position by the spring 38, the levers 71 and 66, the link 63, and the pawl 51 and slide 52 will also return idly to the normal positions shown in Figures 1 and 3.

If the shield 48 is set so as to effect either double or triple line spacing movement of the platen in response to rocking of the lever 29, the operation will be essentially the same as that described above, with the exception that the line

spacing pawl 45 will engage the ratchet wheel 47 earlier in the rocking of the lever 29.

If the left margin stop 19 is adjusted, as shown in Figure 7, so as to engage the center stop assembly 20 to determine an unusually wide right hand margin or indentation on the work sheet, say, with the left hand end of the rubber part of the platen C more than about 2½ inches to the left of the printing point, the pawl 51 on the carriage will be in the range of the serrations 50 on the frame rail 6 when the carriage is in its right end position. If the line spacing and carriage returning lever 29 is rocked with the parts so positioned, the pawl 51 will move into gripping engagement with the rail 6 in the manner previously described, but the carriage will be held against further movement to the right by engagement of the margin stop 19 with the center stop assembly 20. However, the lever 29 can be moved through its full stroke, and the line spacing mechanism operated accordingly, because of the yielding of the link 63, enabling the lever 66 to rock through its full stroke while the connection 65 between the link 63 and the lever 66, which normally acts as a relatively fixed fulcrum, will rock about the pivot 67, which is then stationary on the immobilized carriage. Because of the necessity of stretching the spring link 63 in the performance of such operations, some additional effort must be applied to the lever 29 for effecting line spacing, but this is no substantial disadvantage, since it is only seldom that the margin stop 19 will be set to determine such a wide right hand margin on the work sheet.

It is desirable that the lever 29 be operable for effecting line spacing movement of the platen C without being restrained by the spring 63 and associated parts when the margin stop 19 is set for determining a more normal or usual right hand margin, for example, a margin corresponding to an extreme right hand position of the carriage in which the left end of the rubber part of the platen is located within about 2½ inches of the printing point. To this end, the top surface of the rail 6 is cut away as at 74 at the right end of the rail so as to prevent the gripper pawl 51 from having gripping engagement with this part of the rail. Figure 5 shows the relative positions of the gripper pawl 51 and the rail 6 when the carriage is in such a relatively normal right end position, and when the lever 29 has been rocked for effecting operation of the line spacing mechanism. As shown in Figure 5, the pawl has been moved away from its normal position, but, because of the cutout part 74 in the rail 6, the pawl is not in gripping engagement with the rail. Consequently, the lever 66 may move freely about the pivot 67 accompanied by free movement of the slide 52 on the carriage rail 2 and free movement of the connection 65 between the right end of the link 63 and the lower end of the lever 66 without being restrained by the link 63. Thus, the lever 29 may be rocked by the application of only as much force as is required to operate the line spacing mechanism.

If the carriage is in a paragraphing or indented position, with the pawl 51 above the cutout part 74 of the bar 6, and if the lever 29 is moved only far enough to bring its short arm 42 into engagement with the stop post 35, the line spacing mechanism will be operated but the carriage will not be moved away from its indented position.

The construction shown for the purposes of illustration embodies the invention in a preferred form, but it is intended that the disclosure be

illustrative rather than definitive of the invention. The invention is defined in the claims.

I claim:

1. In a typewriter or like machine, a relatively stationary frame; a carriage mounted on said frame for letter spacing and return movements in opposite directions; means for driving said carriage in the letter spacing direction; a member movably mounted on said carriage and to which effort may be applied for moving said carriage in the return direction; and normally inoperative connections between said member and said frame adapted to be rendered operative during an initial part of the movement of said member on said carriage incident to application of effort to said member for returning said carriage, said connections including a mechanical advantage device for multiplying the effort applied to said member and transmitting the multiplied effort to said carriage, whereby the effort required to be applied to said member for starting the return movement of said carriage is reduced.

2. In a typewriter or like machine, a relatively stationary frame; a carriage mounted on said frame for letter spacing and return movements in opposite directions; means for constraining said carriage against substantial movements transverse to the directions of letter spacing and return travel; means for driving said carriage in the letter spacing direction; and means for moving said carriage in the return direction comprising a normally inoperative member movably mounted on said carriage and being adapted to have mechanical advantage operative connection with said carriage and said frame incident to initial application of effort to said member for exerting force on said carriage only substantially parallel to said directions of letter spacing and return travel for returning said carriage, the mechanical advantage connection multiplying the effort applied to said member, whereby the effort required to be applied to said member for starting the carriage on its return movement is reduced.

3. In a typewriter or like machine, a relatively stationary frame; a carriage mounted on said frame for letter spacing and return movements in opposite directions; means for driving said carriage in the letter spacing direction; a member movably mounted on said carriage and to which effort may be applied for moving said carriage in the return direction; normally inoperative connections between said member and said frame adapted to be rendered operative during an initial part of the movement of said member on said carriage incident to application of effort to said member for returning said carriage, said connections including a mechanical advantage device for multiplying the effort applied to said member and transmitting the multiplied effort to said carriage, whereby the effort required to be applied to said member for starting the return movement of said carriage is reduced; a stop for limiting the movement of said member on said carriage and being operative for causing effort applied to said member to be transmitted directly to said carriage for returning the carriage at the speed at which movement of said member is continued after said stop exerts its limiting effect on said member; and means for rendering said connections inoperative when said stop exerts its limiting effect on said member.

4. In a typewriter or like machine, a relatively stationary frame; a carriage mounted on said frame for letter spacing and return movements

in opposite directions; means for driving said carriage in the letter spacing direction; means for moving said carriage in the return direction comprising a normally inoperative member movably mounted on said carriage and being adapted to have mechanical advantage operative connection with said carriage and said frame incident to initial application of effort to said member for returning said carriage, the mechanical advantage connection multiplying the effort applied to said member, whereby the effort required to be applied to said member for starting the carriage on its return movement is reduced; a stop for limiting the movement of said member on said carriage and being operative for causing effort applied to said member to be transmitted directly to said carriage for returning the carriage at the speed at which movement of said member is continued after said stop exerts its limiting effect on said member; and means for rendering said mechanical advantage connection inoperative when said stop exerts its limiting effect on said member.

5. In a typewriter or like machine, a relatively stationary frame; a carriage mounted on said frame for letter spacing and return movements in opposite directions; means for driving said carriage in the letter spacing direction; a member movably mounted on said carriage and to which effort may be applied for moving said carriage in the return direction; normally inoperative connections between said member and said frame adapted to be rendered operative during an initial part of the movement of said member on said carriage incident to application of effort to said member for returning said carriage, said connections including a mechanical advantage device for multiplying the effort applied to said member and transmitting the multiplied effort to said carriage, whereby the effort required to be applied to said member for starting the return movement of said carriage is reduced; a rotatable sheet feeding platen on said carriage; and line spacing mechanism for turning said platen in response to movement of said member on said carriage when said member is operative through said connections for starting the return movement of said carriage.

6. In a typewriter or like machine, a relatively stationary frame; a carriage mounted on said frame for letter spacing and return movements in opposite directions; means for driving said carriage in the letter spacing direction; means for moving said carriage in the return direction comprising a normally inoperative member movably mounted on said carriage and being adapted to have mechanical advantage operative connection with said carriage and said frame incident to initial application of effort to said member for returning said carriage, the mechanical advantage connection multiplying the effort applied to said member, whereby the effort required to be applied to said member for starting the carriage on its return movement is reduced; a rotatable sheet feeding platen on said carriage; and line spacing mechanism for turning said platen in response to movement of said member on said carriage when said member is operative through said mechanical advantage connection for starting the return movement of said carriage.

7. In a typewriter or like machine, a relatively stationary frame; a carriage mounted on said frame for letter spacing and return movements in opposite directions; means for driving said

carriage in the letter spacing direction; a member movably mounted on said carriage and to which effort may be applied for moving said carriage in the return direction; and normally inoperative connections between said member and said frame including a first part mounted on said carriage and a cooperable second part on said frame extending throughout only a part of the range of movement of said first part incident to carriage movement on said frame and being adapted to be rendered operative during an initial part of the movement of said member on said carriage incident to application of effort to said member for returning said carriage, said connections including a mechanical advantage device for multiplying the effort applied to said member and transmitting the multiplied effort to said carriage, whereby the effort required to be applied to said member for starting the return movement of said carriage is reduced.

8. In a typewriter or like machine, a relatively stationary frame; a carriage mounted on said frame for letter spacing and return movements in opposite directions; means for driving said carriage in the letter spacing direction; a member movably mounted on said carriage and to which effort may be applied for moving said carriage in the return direction; normally inoperative connections between said member and said frame including a first part mounted on said carriage and a cooperable second part on said frame extending throughout only a part of the range of movement of said first part incident to carriage movement on said frame and being adapted to be rendered operative during an initial part of the movement of said member on said carriage incident to application of effort to said member for returning said carriage, said connections including a mechanical advantage device for multiplying the effort applied to said member and transmitting the multiplied effort to said carriage, whereby the effort required to be applied to said member for starting the return movement of said carriage is reduced; a stop for limiting the movement of said member on said carriage and being operative for causing effort applied to said member to be transmitted directly to said carriage for returning the carriage at the speed at which movement of said member is continued after said stop exerts its limiting effect on said member; and means for rendering said connections inoperative when said stop exerts its limiting effect on said member.

9. In a typewriter or like machine, a relatively stationary frame; a carriage mounted on said frame for letter spacing and return movements in opposite directions; means for driving said carriage in the letter spacing direction; and means for moving the carriage in the return direction including a lever, a pivot mounting said lever on said carriage, said lever having a part to which effort may be applied for rocking said lever about said pivot, a fulcrum for said lever, and means for anchoring said fulcrum to said frame, the lever arm between said lever part and said fulcrum being longer than the lever arm between said pivot and said fulcrum, whereby the mechanical advantage so provided reduces the effort required to be applied to said lever part for starting the return movement of the carriage.

10. In a typewriter or like machine, a relatively stationary frame; a carriage mounted on said frame for letter spacing and return movements in opposite directions; means for driving said carriage in the letter spacing direction; and means

for moving the carriage in the return direction including a lever, a pivot mounting said lever on said carriage, said lever having a part to which effort may be applied for rocking said lever about said pivot, a fulcrum for said lever, and means for anchoring said fulcrum to said frame including a device connected to said fulcrum and being movable with said carriage, and a cooperable part on said frame extending throughout only a portion of the range of movement of said device with said carriage, the lever arm between said lever part and said fulcrum being longer than the lever arm between said pivot and said fulcrum whereby the mechanical advantage so provided reduces the effort required to be applied to said lever part for starting the return movement of the carriage.

11. In a typewriter or like machine, a relatively stationary frame; a carriage mounted on said frame for letter spacing and return movements in opposite directions; means for driving said carriage in the letter spacing direction; and means for moving the carriage in the return direction including a lever, a pivot mounting said lever on said carriage, said lever having a part to which effort may be applied for rocking said lever about said pivot, a fulcrum for said lever, and means for anchoring said fulcrum to said frame including a gripper pawl connected to said fulcrum and being movable with said carriage, and a cooperable bar on said frame extending throughout only a portion of the range of movement of said gripper pawl with said carriage, the lever arm between said lever part and said fulcrum being longer than the lever arm between said pivot and said fulcrum, whereby the mechanical advantage so provided reduces the effort required to be applied to said lever part for starting the return movement of the carriage.

12. In a typewriter or like machine, a relatively stationary frame; a carriage mounted on said frame for letter spacing and return movements in opposite directions; means for driving said carriage in the letter spacing direction; means for moving the carriage in the return direction including a lever, a pivot mounting said lever on said carriage, said lever having a part to which effort may be applied for rocking said lever about said pivot, a fulcrum for said lever, and means for anchoring said fulcrum to said frame, the lever arm between said lever part and said fulcrum being longer than the lever arm between said pivot and said fulcrum, whereby the mechanical advantage so provided reduces the effort required to be applied to said lever part for starting the return movement of the carriage; a stop for limiting the movement of said lever on said carriage and being operative for causing effort applied to said lever to be transmitted directly to said carriage for returning the carriage at the speed at which movement of said lever is continued after said stop exerts its limiting effect on said lever; and means for rendering said fulcrum anchoring means inoperative when said stop exerts its limiting effect on said lever.

13. In a typewriter or like machine, a relatively stationary frame; a carriage mounted on said frame for letter spacing and return movements in opposite directions; means for driving said carriage in the letter spacing direction; and means for moving the carriage in the return direction including a lever, a pivot mounting said lever on said carriage, said lever having a part to which effort may be applied for rocking said lever about said pivot, a fulcrum for said lever, and means for

anchoring said fulcrum to said frame including a bar on said carriage extending in the direction of carriage travel, a gripper mounted on said carriage for movement into and out of gripping engagement with said bar and for limited movement on the carriage parallel to said bar, and a link connecting said gripper to said fulcrum and being operative upon initial movement of said lever for moving said gripper into gripping relation to said bar, the lever arm between said lever part and said fulcrum being longer than the lever arm between said pivot and said fulcrum, whereby the mechanical advantage so provided reduces the effort required to be applied to said lever part for starting the return movement of the carriage.

14. In a typewriter or like machine, a relatively stationary frame; a carriage mounted on said frame for letter spacing and return movements in opposite directions; means for driving said carriage in the letter spacing direction; and means for moving the carriage in the return direction including a lever, a pivot mounting said lever on said carriage, said lever having a part to which effort may be applied for rocking said lever about said pivot, a fulcrum for said lever, and means for anchoring said fulcrum to said frame including a serrated bar on said carriage extending in the direction of carriage travel, a gripper pawl mounted on said carriage for movement into and out of gripping engagement with said bar and for limited movement on the carriage parallel to said bar, and a yieldable link connecting said pawl to said fulcrum and being operative upon initial movement of said lever for moving said pawl into gripping relation to said bar, the lever arm between said lever part and said fulcrum being longer than the lever arm between said pivot and said fulcrum, whereby the mechanical advantage so provided reduces the effort required to be applied to said lever part for starting the return movement of the carriage.

15. In a typewriter or like machine, a relatively stationary frame; a carriage mounted on said frame for letter spacing and return movements in opposite directions; means for driving said carriage in the letter spacing direction; a serrated bar fixed with respect to said frame and extending in the direction of carriage travel; a pawl; means mounting said pawl on said carriage for movement transverse to said bar towards and from a position of engagement with said bar and for limited movement on said carriage parallel to said bar; a lever; a pivot mounting said lever on said carriage; a part on said lever adapted to receive applied effort tending to rock said lever; and a link connecting said lever to said pawl and being operable upon initial rocking of said lever for moving said pawl into engagement with said bar whereby movement of the connection between said link and said lever in the direction of carriage travel will be resisted and continued movement of said lever will drive said carriage through said pivot to start the carriage on its return movement.

16. In a typewriter or like machine, a relatively stationary frame; a carriage mounted on said frame for letter spacing and return movements in opposite directions; means for driving said carriage in the letter spacing direction; a bar fixed with respect to said frame and extending in the direction of carriage travel and having a serrated portion extending from the left

end portion of said bar, as viewed from the front of the machine, towards but terminating short of the right end of said bar; a pawl; means mounting said pawl on said carriage for movement transverse to said bar towards and from a position of engagement with the serrated portion of said bar and for limited movement on said carriage parallel to said bar; a lever; a pivot mounting said lever on said carriage; a part on said lever adapted to receive applied effort tending to rock said lever; and a link connecting said lever to said pawl and being operable upon initial rocking of said lever for moving said pawl into engagement with the serrated portion of said bar whereby movement of the connection between said link and said lever in the direction of carriage travel will be resisted and continued movement of said lever will drive said carriage through said pivot to start the carriage on its return movement.

17. Construction as set forth in claim 15 in which the lever arm between said part of said lever and the connection of said lever to said link is longer than the lever arm between said pivot and the connection of said lever to said link.

18. In a typewriter or like machine, a relatively stationary frame; a carriage mounted on said frame for letter spacing and return movements in opposite directions; means for driving said carriage in the letter spacing direction; a bar fixed with respect to said frame and extending in the direction of carriage travel and having a serrated portion extending from the left end of said bar, as viewed from the front of said machine, towards but terminating short of the right end of said bar; a member mounted on said carriage for limited sliding movement relative to the carriage; a gripper mounted on said member for movement into and out of engagement with the serrated portion of said bar; a lever having one of its ends formed to receive effort applied to said lever for effecting carriage return movement; a pivot fixed to said carriage and mounting said lever to rock about an axis intermediate the lever ends; and means including a link connecting said gripper to the other of said lever ends and being operative by initial rocking of said lever for moving said gripper into engagement with the serrated portion of said bar, whereby said gripper and said link will hold said other of said lever ends against substantial movement in the direction of carriage travel so that continued rocking of said lever will exert driving force through said pivot to start the return movement of said carriage with the mechanical advantage provided by said lever.

19. In a typewriter or like machine, a relatively stationary frame; a carriage mounted on said frame for letter spacing and return movements in opposite directions; means for driving said carriage in the letter spacing direction; a bar fixed with respect to said frame and extending in the direction of carriage travel and having a serrated portion extending from the left end of said bar, as viewed from the front of said machine, towards but terminating short of the right end of said bar; a member mounted on said carriage for limited sliding movement relative to the carriage; a gripper mounted on said member for movement into and out of engagement with the serrated portion of said bar; a lever having one of its ends formed

to receive effort applied to said lever for effecting carriage return movement; a pivot fixed to said carriage and mounting said lever to rock about an axis intermediate the lever ends; means including a link connecting said gripper to the other of said lever ends and being operative by initial rocking of said lever for moving said gripper into engagement with the serrated portion of said bar, whereby said gripper and said link will hold said other of said lever ends against substantial movement in the direction of carriage travel so that continued rocking of said lever will exert driving force through said pivot to start the return movement of said carriage with the mechanical advantage provided by said lever; a stop for arresting rocking of said lever after it has rocked far enough to start the return movement of said carriage and for then providing a direct drive connection between said lever and said carriage effective independently of said link and said gripper for effecting continued return movement of said carriage; and means for disengaging said gripper from the serrated part of said bar in response to return movement of said carriage following engagement of said lever with said stop.

20. In a typewriter or like machine, a relatively stationary frame; a carriage mounted on said frame for letter spacing and return movements in opposite directions; means for driving said carriage in the letter spacing direction; a bar fixed with respect to said frame and extending in the direction of carriage travel and having a serrated portion extending from the left end of said bar, as viewed from the front of said machine, towards but terminating short of the right end of said bar; a member mounted on said carriage for limited sliding movement relative to the carriage; a gripper mounted on said member for movement into and out of engagement with the serrated portion of said bar; a lever having one of its ends formed to receive effort applied to said lever for effecting carriage return movement; a pivot fixed to said carriage and mounting said lever to rock about an axis intermediate the lever ends; means including a link connecting said gripper to the other of said lever ends and being operative by initial rocking of said lever for moving said gripper into engagement with the serrated portion of said bar, whereby said gripper and said link will hold said other of said lever ends against substantial movement in the direction of carriage travel so that continued rocking of said lever will exert driving force through said pivot to start the return movement of said carriage with the mechanical advantage provided by said lever; a rotatable paper feeding platen on said carriage; line spacing mechanism for rotating said platen; a combined line spacing and carriage returning handle pivotally mounted on said carriage and operatively connected to said mechanism; and gear connections between said handle and said one of said ends of said lever.
